UNITED STATES PATENT OFFICE

SAMUEL BERGSTEIN, OF MIDDLETOWN, OHIO

PAPER BOX OR THE LIKE

Application filed March 12, 1928. Serial No. 261,000.

This invention relates to improvements in paper boxes.

In the accompanying drawings which serve for illustrating the invention:

5 Fig. 1 is a diagrammatic view of the box blank for the body of the box as cut from the paper sheet:

Fig. 2 is a diagrammatic view of the blank for the lid of the box:

10 Fig. 3 is a detail view of an end of the body of the box:

Fig. 4 is a detail view of an end of the lid.

Fig. 5 is a detail view illustrating a modification.

15 An object attained in the invention consists in a paper box designed for minimizing the amount of material required in the construction of the box and for reducing the waste of material in cutting the box stock 20 to a negligible amount.

A further object attained in the improved box consists in severing opposite sealing flaps from the inner end flaps for reinforcing the body of the box by extending the 25 sealing flaps outwardly substantially beyond and downwardly from the upper edge of the box at the corners, thus effecting construction of great strength at the upper corners of the box with a relatively small amount of 30 material.

The corner construction of the lid of the box is similar to that of the body except that the outer end flap is folded for effecting double thickness of material at the ends of 35 the lid and the reinforcing flaps are extended inward and glued to the side walls of the lid.

The structure of the body of the box, as 40 shown in Figs. 1 and 3, consists in the bottom 1, sides 2, outer end flaps 3, inner end flaps 4, reinforcing upper corner flaps 5, the latter together with the upper portion of the inner faces of flaps 3 being supplied with 45 adhesive as indicated at —a for effecting a glued end and corner construction. For minimizing the amount of material required for constructing the box and the waste of material in cutting the box stock, the corner 50 flaps 5 are cut from the lower corners of the

free ends of flaps 3 as indicated at 6, thus without weakening the end construction.

The reinforced upper corner construction, as illustrated in Fig. 3 presents double thickness of material along the upper edges of 55 the end and side walls of the box, thus giving added strength where it is most needed to prevent breaking or tearing of the material on the corner line which results in boxes of ordinary construction in handling the same 60 incident to their use. It will be apparent that the flaps 5 may be made any desired length vertically, for extending the reinforcement any desired distance along the corners of the box; also that by slightly 65 modifying the shape of flaps 5 the construction may be readily changed from the glued to the lock-flap type of box, as illustrated in Fig. 5 of the drawings.

The lid of the box, as shown in Figs. 2 70 and 4, consists of the top 7, sides 8, outer end fold 9, inner end fold 10, side end flaps 11, and corner reinforcing flaps 12, the latter together with the end portion 10 being supplied with adhesive as indicated at —a for 75 gluing parts 10—11—12 and 8 together. The inward fold of the end portion 10 over parts 9 and 11 and extension of flaps 12 along the sides 8 results in an end and corner construction of the lid of relatively great 80 strength, there being double thickness of material across the end, and double and treble thickness of material respectively on opposite sides adjacent the corners.

Any suitable means may be employed for 85 constructing the boxes. For small quantity production simple hand operated presses will serve for assembling the several parts of the box. For large production automatic or semi-automatic box assembling machines 90 will be used, and machines adapted for simultaneously sealing the reinforced corners along both sides of the corner line will be preferred. The principle for such a machine is set forth in my copending application for 95 patent filed March 12, 1928 for means and method for making paper boxes.

I claim as my invention:

A paper box including a portion comprising 100 a bottom, opposite side walls, end flaps

attached to the side walls, and end walls attached to said bottom including corner reinforcing flaps severed from adjacent corners of said end flaps, said reinforcing flaps being secured as the box is assembled to the side walls outward at the upper portions of the corners of the box with said end flaps inward of the end walls and the vertical edges thereof in close proximity one with the other
5 and the recesses formed by severing the corner reinforcing flaps therefrom adjacent the bottom of the box, effecting double wall thickness of the ends of the box except as to the portions adjacent said recesses.
10

15 In testimony whereof, I affix my signature.
SAMUEL BERGSTEIN.
